(57) **CLAIM**

The ornamental design for an ultrasonic probe, as shown and described.

DESCRIPTION

FIG. 1 is a front view of an ultrasonic probe showing our new design.

FIG. 2 is a left view of the ultrasonic probe design shown in FIG. 1;

FIG. 3 is a front perspective view of the ultrasonic probe design shown in FIG. 1;

FIG. 4 is a rear perspective view of the ultrasonic probe design shown in FIG. 1;

FIG. 5 is a bottom perspective view of the ultrasonic probe design shown in FIG. 1;

FIG. 6 is a top view of the ultrasonic probe design shown in FIG. 1;

FIG. 7 is a rear view of the ultrasonic probe design shown in FIG. 1;

FIG. 8 is a right view of the ultrasonic probe design shown in FIG. 1; and,

FIG. 9 is a bottom view of the ultrasonic probe design shown in FIG. 1.
